UNITED STATES PATENT OFFICE.

GEORGE CROUCH, OF NEW YORK, N. Y.

DESIGN FOR A TRUNK-SLAT.

SPECIFICATION forming part of Design No. 28,563, dated May 10, 1898.

Application filed December 20, 1897. Serial No. 662,751. Term of patent 14 years.

To all whom it may concern:

Be it known that I, GEORGE CROUCH, a citizen of the United States, residing at the city of New York, in the county and State of New York, have invented and produced a new and original Design for a Trunk-Slat, of which the following is a specification.

Trunk-slats have been made with straight parallel edges, usually rounded on the edges and reduced in thickness at the ends.

The leading feature of this design for a trunk-slat is the undulating edge composed of a series of reverse curves, that gives to the slat an ornamental appearance.

In the drawings, Figure 1 represents the

design of the slat. Fig. 2 is a longitudinal edge view, and Fig. 3 is a cross-section.

The edge of the slat, instead of being straight, is undulating and composed of concave portions *a* and convex portions *b*.

20

I claim—

The design for a trunk-slat, substantially as shown and described.

Signed by me this 16th day of December, 1897.

GEO. CROUCH.
